UNITED STATES PATENT OFFICE.

WILLIAM R. JEAVONS, OF CLEVELAND, OHIO.

DESIGN FOR AN OIL-STOVE.

SPECIFICATION forming part of Design No. 35,866, dated April 15, 1902.

Application filed December 23, 1901. Serial No. 87,044. Term of patent 7 years.

To all whom it may concern:

Be it known that I, WILLIAM R. JEAVONS, a citizen of the United States, residing in the city of Cleveland, in the county of Cuyahoga and State of Ohio, have invented a new and original Design for Oil-Stoves, of which the following is a specification, reference being had to the accompanying drawing, forming part thereof.

10 The single figure of the drawing herein shown is a perspective elevation of my said new and original design in oil-stoves, and the leading or material feature of my design as thus shown is seen in the novel appearance 15 of the stove as a whole and as it addresses itself to the eye with all the more prominent features included rather than in any particular detail or feature alone. In this wholeness of appearance the unitary or single burner 20 characteristic of the design is especially conspicuous and as such is constituted of a sin-

gle drum A in its center, a base B, broken-surfaced top C, and uprights D between bottom B and top C. At one side of the design is an inclined stem E, and at another side ²⁵ there is a somewhat-elongated figure G of practically plain outline with closed top and having a stem J, apparently connecting with its bottom. The whole and complete design comprises these features in their associated ³⁰ relations, substantially as shown and described.

What I claim is—

The design for an oil-stove, substantially as shown and described. ³⁵

Witness my hand to the foregoing specification this 19th day of December, 1901.

WILLIAM R. JEAVONS.

Witnesses:

R. B. MOSER,
T. M. MADDEN.
